UNITED STATES PATENT OFFICE

FRANK WATSON, OF BALTIMORE, MARYLAND

FOLDING BOX

Application filed July 12, 1929. Serial No. 377,806.

This invention relates to a folding box, preferably made of corrugated paperboard, and adapted particularly for containing stacks of post card sheets, or other paper 5 sheets of value, which are to be shipped by express or through the mails. These sheets are usually counted before being boxed for shipment, and in case shortage is found when the box arrives at its destination, it 10 becomes important to know whether the shortage is due to a miscount at the sending office, or whether the box has been tampered with and sheets removed while in transit.

The purpose of my invention is to provide 15 a light and strong box in which such stacks of post card sheets may be transported, which cannot be opened except by mutilation of the box, and which is provided with a sealing strip so affixed to the box that any 20 attempt to remove the strip and replace it with another will be apparent upon inspection of the box. Thus, if the box arrives at its destination unbroken and with the original sealing strip in perfect condition, it 25 may be opened and if there happens to be a shortage in the number of card sheets in the box, it will be evident that there has been a mis-count of the sheets in packing the box. On the other hand, if the original seal is 30 not in place and in perfect condition, the receiver of the box will know that an attempt has been made to tamper with the box and he may refuse to receive or open it, and thus he will not be charged with any 35 shortage that may afterwards be found.

In the accompanying drawings,

Fig. 1 is a perspective view of a box made in accordance with my invention;

Fig. 2 is a transverse section on the line 40 2-2 of Fig. 1;

Fig. 3 is a longitudinal section on the line 3-3 of Fig. 1, partly broken away;

Fig. 4 is a section through a corner of the box, on the line 4-4 of Fig. 1;

Fig. 5 is a perspective view of a blank 45 from which the box is made, partly folded, and showing also in dotted lines a package to be enclosed by the box, and in full lines, a portion of the board to which the top portions are sealed when the box is closed;

Fig. 6 is a perspective view of one end of the box, with the sealing strip extending over the end flap.

Referring first to Fig. 5 of the drawings, the blank from which the box is made comprises a rectangular base 1, end flaps 2, side flaps 3 of approximately the same length as the base, said end and side flaps being connected to the base along creased lines *a* and *b*, respectively. Cover portions 4 55 each approximately equal in width to half the width of the base, are connected to the side flaps along creased lines *c*, and each cover portion has end flaps 5 to which are connected corner flaps 6. The flaps 6 are formed by slotting the blank inwardly from its ends, as shown at 7, to the points where the creased lines *a* and *b* meet and thence along the creased lines *a* to the creased lines *c*, as indicated at 8.

In folding the blank, the corner flaps 6 are turned at right angles to the flaps 5, and the latter are then turned at right angles to the cover portions 4, and the latter portions are turned at right angles to the sides 3, as shown at the left side of Fig. 5. By then turning the sides 3 at right angles to the base, the edges 4^a of the cover portions and the edges 5^a of the flaps 5 will meet along the longitudinal center line of 80 the box. The end flaps 2 are then turned upwardly against the end flaps 5 to complete the folding of the blank. It is to be noted that when the box is set up it has a 85 double thickness of material at the corners.

In packing a stack of paper cards, indicated at *d* in Fig. 5, the stack is laid upon the base 1 and a sheet of stiff paperboard *e*, of corresponding length and width, is laid upon the stack. The height of the stack plus the thickness of this board is just sufficient to fill the box. A coating of adhesive substance, such as silicate of soda, is then applied to the top of the board *e* and the sides and top portions of the box are then 90 folded over the stack *d* and board *e*, in the manner heretofore described. The top portions are thus brought into contact with the coated surface of the board *e* and they 95 become securely affixed to the board when the 100

coating dries. After folding the top and side portions of the box, a sealing strip *f*, which may be a strip of tough paper having an adhesive coating on one side, is laid 5 along the central longitudinal part of the box and cemented to the box, and the ends *f'* of the strip are extended downwardly on the end flaps 5 of the cover portion, as shown in Figs. 1, 2 and 3. The meeting edges 4^a 10 of the cover portion and the meeting edges 5^a of the flaps 5 are thus covered and sealed by the strip. A coating of strong adhesive material, such as silicate of soda, is then applied to the end flaps 2 of the base portion and these are turned upwardly against the flaps 5 and the ends *f'* of the sealing strip. Pressure is applied to the top and ends of the box until the adhesive has dried.

The board *e* reinforces the top of the box 20 and being adhesively secured to the top, it is impossible to separate the top portion without destroying the top of the box. Similarly, the end flaps 5, being adhesively secured to the flaps 2, cannot be opened except by mutilation of the box ends. The 25 sealing strip *f* is provided in order to detect tampering with the box. If the strip extended only over the top portion of the box, it might be removed and replaced by another strip, without detection, but by extending the ends of the sealing strip downwardly between the flaps 2 and 5 and by cementing these flaps together, it becomes impossible to remove and replace the entire 30 strip, and if the strip is not continuous with its ends sealed in, when the box arrives at its destination, it will be evident that an attempt has been made to open the box.

Where the box is used for shipping articles which are not likely to be stolen and 40 where it is not important to detect tampering with the box, the ends of the sealing strip may be brought down on the outer sides of the ends of the box and cemented to its ends, as shown in Fig. 6.

What I claim is:

1. A folding box comprising a base, side walls hinged to the base and of the same length as the base, cover portions hinged 50 to the side walls and each approximately half the width of the base, said cover portions meeting edge to edge along the longitudinal center of the box, end flaps on the cover portions extending downwardly to the base, corner flaps, of approximately the same width as the side walls, hinged to said end flaps and folded inwardly against the side walls, and end flaps on the base folded against the end flaps on the cover 55 portions.

2. A folding box comprising a base, side walls hinged to the base and of the same length as the base, cover portions hinged 60 to the side walls and each approximately half the width of the base, said cover por-

tions meeting edge to edge along the longitudinal center of the box, end flaps on the cover portions extending downwardly to the base, rectangular corner flaps, of approximately the same width as the side walls, hinged to said end flaps and folded inwardly against the side walls, and end flaps on the base folded against the end flaps on the cover portions.

3. A folding box comprising a base, side walls hinged to the base and of the same length as the base, cover portions hinged to the side walls and each approximately half the width of the base, said cover portions meeting edge to edge along the longitudinal center of the box, end flaps on the cover portions extending downwardly to the base, corner flaps, of approximately the same width as the side walls, hinged to said end flaps and folded inwardly against the side walls, a board cemented to the inner sides of the cover portions and the end flaps on the base being folded against and sealed to the end flaps on the cover portions.

4. A folding box comprising a base, side walls hinged to the base and of the same length as the base, cover portions hinged to the side walls and each approximately half the width of the base, said cover portions meeting edge to edge along the longitudinal center of the box, end flaps on the cover portions extending downwardly to the base, corner flaps, of approximately the same width as the side walls, hinged to said end flaps and folded inwardly against the side walls, end flaps on the base and a sealing strip extending longitudinally of the box over the meeting edges of the cover portions and thence downwardly on the end flaps of the cover portions, the end flaps on the base being folded against and cemented to the end flaps on the cover portions and covering the ends of the sealing strip.

5. A folding box comprising a base, side walls hinged to the base and of the same length as the base, cover portions hinged to the side walls and each approximately half the width of the base, said cover portions meeting edge to edge along the longitudinal center of the box, end flaps on the cover portions extending downwardly to the base, corner flaps, of approximately the same width as the side walls, hinged to said end flaps and folded inwardly against the side walls, end flaps on the base, a board cemented to the inner sides of the cover portions and a sealing strip extending longitudinally of the box over the meeting edges of the cover portions and downwardly on the end flaps of the cover portions, the end flaps on the base being folded against and cemented to the end flaps on the cover portions and covering the ends of the sealing strip.

In testimony whereof I affix my signature.

FRANK WATSON.
